CARRIER FOR LAUNDRY MATERIALS

Marshall Dale Reiss, 3225 Audubon, East St. Louis, Ill.

Filed May 1, 1963, Ser. No. 74,697

Term of patent 7 years

(Cl. D58—26)

FIG. 1.

FIG. 2.

FIG. 3.

FIG. 4.

FIG. 1 is a top plan view of a carrier for laundry materials, showing my new design.

FIG. 2 is a perspective view of the carrier.

FIG. 3 is an end elevational view of the carrier.

FIG. 4 is a side elevational view of the carrier.

The undisclosed side of the carrier is substantially the same in appearance as the side shown.

I claim:

The ornamental design for a carrier for laundry materials, substantially as shown and described.
